UNITED STATES PATENT OFFICE.

JAMES P. HILLARD, OF FALL RIVER, MASSACHUSETTS.

IMPROVEMENT IN STEPS FOR SPINDLES TO SPINNING-MACHINES.

Specification forming part of Letters Patent No. 99,087, dated January 25, 1870.

To all whom it may concern:

Be it known that I, JAMES P. HILLARD, of Fall River, in the county of Bristol, in the State of Massachusetts, have invented a new and Improved Step for Spindles to Spinning-Machines. I do hereby declare that the following is a full and exact description thereof, reference being had to the accompanying drawings, and to letters of reference marked thereon.

My invention consists in a spindle-step and oil-cap combined.

Figure 1 is a perspective view of spindle-step and cap combined, with spindle inserted into it. Fig. 2 is a section of spindle, spindle-step, and oil-cap. Fig. 1—A¹ is spindle-step; B¹, oil-cap; C¹, spindle. Fig. 2—A² is spindle-step; B², oil-cap; C², spindle.

Operation: The spindle-step being cast,

with oil-cap combined, as herein shown, with apertures a² b², as also shown, its operation may be noted.

The spindle being inserted in the step, as seen in Fig. 1, and the oil for lubrication inserted through aperture a², the aperture b² permits the air to escape as the oil takes its place. Its operation may be noted without further specification.

What I claim as my invention, and desire to secure by Letters Patent, is—

The spindle-step A¹, and oil-cap B¹, and apertures a² b², combined and constructed as herein set forth and described, for the purpose specified.

JAMES P. HILLARD.
